POWER MANICURING DEVICE

Filed May 26, 1930

UNITED STATES PATENT OFFICE

GUSTAVE LIDSEEN, OF CHICAGO, ILLINOIS

POWER MANICURING DEVICE

Application filed May 26, 1930. Serial No. 455,529.

This invention relates to a power actuated manicuring tool or device.

The invention contemplates a compact casing containing a rotatable member and means for actuating said member, and a plurality of tools adapted for removably attaching to said member for performing the various operations in manicuring.

The device comprises a casing containing a vibratable armature which is connected to a spring at one end, said spring being adjustable to vary the stroke of said armature. The other end of the armature carries a cuticle pusher, and is also connected to a mechanism which changes the vibratory motion of the armature into a rotary motion which is imparted to anyone of a number of rotary tools which may be connected to said mechanism. A coil is provided for vibrating the armature, said coil being arranged for energizing either from alternating or direct current without any change in the construction of the device.

It is an object of this invention to provide an electrically operated manicuring device which is compact, easy to use, which is operable by either direct or alternating current, which is efficient in use and economical to manufacture.

Another object of this invention is to provide a manicuring device having a rotary tool and power means for actuating said tool.

It is a further object of this invention to provide an electrically operated manicuring device in which a vibrating arm carries a tool for use in certain of the operations incidental to manicuring, and at the same time functions to drive a mechanism which is connected to a rotary tool for use in other of the operations.

It is also an object of this invention to provide a manicuring machine in which a plurality of rotatable tools may be used, said tools being easily and quickly interchangeable for performing the various operations incident to manicuring.

Other and further important objects of this invention will be apparent from the disclosures in the accompanying drawing and the following specification.

The invention (in a preferred form) is illustrated on the drawing and hereinafter more fully described.

On the drawing:

Figure 1 is a top plan view of a manicuring device which embodies the features of this invention.

Figure 2 is an end elevational view looking toward the tool end of the device shown in Figure 1.

Figure 3 is an end elevational view looking at the electrical connection end of the device as shown in Figure 4.

Figure 4 is an inverted side elevational view of the device showing the screw for adjusting the tension of the armature.

Figure 5 is an enlarged plan view of the device with the top portion of the casing removed, showing the relationship of the various operative elements of the device.

Figure 6 is an enlarged sectional view of the tool end of the device, taken substantially on line VI—VI of Figure 5.

Figure 7 is an enlarged fragmental view showing the details of the double-pawl ratchet device, taken substantially on line VII—VII of Figure 6.

On the drawing:

In the illustrated embodiment of this invention, there is shown a casing formed of a top portion 1 and a bottom portion 2 which are held together in operative relation by bolts 3 and 4. The top and bottom portions of this casing are formed with depressions 5 and 6 respectively, which are in confronting relationship and form an enlarged section in the container for receiving the marginal portions of an energizing coil 7.

The energizing coil is disposed around one leg of a U-shaped core 8 and held against a supporting plate or frame 9 by means of bolts 10 which extend through the core and engage the plate. This plate lies in the bottom portion 2 of the casing and is secured thereto by appropriate means. Lateral projections 11 are integrally formed with said plate and serve to position the same within the casing. This plate also has an upturned lug 12 having a concave surface. An armature 13 is attached at one end to a spring 14

by means of a large headed screw 15. The other end of the spring 14 is retained against the concave surface of the lug 12 by an adjusting screw 15 having a reduced portion 16 which extends through the spring and threadedly engages the lug 12, the shoulder 17 of the screw head bearing against the spring 14. It is therefore obvious that by tightening or loosening the screw 15, the pressure on the spring 14 may be varied to regulate the vibration of the armature 13. A pole piece 18 is secured to the armature in position to be influenced by the magnetizing forces set up in the core 8 when the coil 7 is energized. The free end of the armature 13 is bent at an angle to form a portion 19 which projects through an aperture 20 of the casing 2 and carries at its outer end a rubber tip 21 which serves as a cuticle set or pusher, when the arm 13 is vibrated. A rubber stop member 22 which is positioned near the free end of the armature 13, serves to cushion said armature when moved outwardly by the spring 14, and also prevents it from striking the casing 2.

A double-pawl ratchet mechanism is provided for transforming the vibratory motion of the armature 13 into a rotary motion. A stub shaft 23 is secured to an upwardly offset portion 24 at one end of the plate 9, and projects outwardly through an aperture 25 in the top portion 1 of the casing. A tubular sleeve 26 having a ratchet wheel 27 secured to one end thereof is rotatably mounted upon the stub shaft 23, the ratchet wheel being positioned adjacent the inner end of said shaft and the outer end of the sleeve projecting to the outside of the casing. The sleeve 26 is provided with a pair of parallel apertures 28 which penetrate the inner wall of the sleeve and communicate with a circumferential groove 29 formed in the stub shaft 23. A U-shaped pin having each leg thereof disposed in one of said apertures prevents the removal of the ratchet wheel and sleeve from the stub shaft, but permits the same to rotate freely thereon. Intermittent rotary motion is imparted to the ratchet wheel 27 by means of a pair of pawls 30 and 31 which are pivotally mounted between the arms of a yoke member 32 carried by the armature 13, said pawls being secured by a U-shaped pin 33 each leg of which extends through the yoke arm and flange 33 formed at the end of each pawl. A spring 34 which is also secured to the yoke member is provided with curved ends which bear against the pawls 30 and 31 and hold the free ends thereof in engagement with the toothed periphery of the ratchet wheel 27.

The free end of the pawl 30 terminates in a hook 35 which will engage the toothed periphery of the ratchet wheel and pull the same in a clockwise direction when the armature 13 moves away from the ratchet wheel.

The pawl 31 is formed so that the free end thereof engages the toothed periphery of the ratchet wheel 27 and pushes it in a clockwise direction when the armature moves toward the ratchet wheel. Since each pawl is designed so as to slide over the teeth when the other pawl is functioning to advance said ratchet wheel, it is apparent that, as long as the armature 13 vibrates back and forth, an intermittent rotary motion will be imparted to the ratchet wheel.

A variety of interchangeable rotary tools is provided for performing the various operations required in manicuring. These tools may be provided with filing surfaces, buffing surfaces, and the like as required, means being provided for quickly and easily attaching any desired tool. To illustrate the construction and means for attaching the tools, a rotary file 36 is shown. The file 36 comprises a disc portion 37 having cutting grooves in the outer surface thereof, and terminating in a circumferential flange 38 which is similarly grooved upon its outer surface. The central portion of the disc terminates in a sleeve 39 which fits coaxially over the sleeve 26 and is held against longitudinal movement by an inwardly projecting nib 40 which engages a circumferential groove 41 in the sleeve 26. The sleeve 39 is also provided with a longitudinally extending slot 41a at one end for receiving a pin 42a carried by the ratchet wheel 27, thereby causing the sleeve 39 and ratchet wheel to rotate as a unit. The rotary tool is prevented from becoming accidentally disengaged from the sleeve 26 by means of a guard plate 42 which is pivotally secured by a screw 43 to the casing 1. This guard plate is provided with a depression 44 for receiving the end of the stub shaft 23, thereby latching the guard in position over the rotary tool. The free end of the guard plate 42 projects past the edge of the rotary tool and terminates in a curved edge 45, which serves as an upper finger rest. A lower nail rest is formed by a lug 46 on the top portion 1 of the casing, said lug being positioned on the opposite side of the rotary tool from the upper finger rest. When it is desired to remove a rotary tool from the device, the guard 42 is swung to the position shown in dotted lines in Figure 1.

The casing is narrowed at one end so that the rotary tool 36 will overhang the edge 47, the casing thereby in no way interfering with the application of the rotary tool in the manicuring operation.

A make and break device comprising an arm 48 and an arm 49 is secured to one of the lateral projections 11 by means of a screw 50 which threadedly engages a plate 51. Separating blocks 52 are suitably placed for insulating the arms 48 and 49. The arm 48 carries a contact point 53 and the arm 49 a contact point 54, said points

normally being in engagement. The armature 13 carries a pair of spaced arms 55 of insulating material which are disposed on either side of the projecting end of the arm 49 of the make and break device to open or separate the contacts 53 and 54, when the armature 13 is moved toward the coil 7.

Electrical connection is made to the manicuring device by means of a two-point plug, not shown in the drawing, which is inserted in the open end of a socket 56 which is secured to the end of plate 9 and projects through an opening 57 in the end of the casting opposite the rotary tool. The socket 56 is provided with three prongs A, B, and C which are formed so as to make contact with mating members in the insertable plug. When the two-point plug is disposed in the socket 56 so as to make contact with the prongs A and C, electrical connection is established directly to the coil 7 through conductors 58 and 59. This connection should only be used when operating the device from an alternating current supply.

When it is desired to operate the device from a direct current supply, the plug is inserted in the socket 56 so as to make contact with the prongs A and B, which establishes one connection directly to the coil 7 through conductor 59. The other side of the circuit will be through conductor 60 to the arm 49, through the contact points 54 and 53 to arm 48, and thence through conductors 61 and 58 to the coil.

The operation of the manicuring device is as follows:

When alternating current is used, the plug is inserted in the socket so as to contact the proper prongs as hereinbefore described, whereupon the coil 7 is alternately energized and deenergized. When the coil is energized, the armature 13 will be attracted and moved downwardly against the pressure of the spring 14. This downward motion of the armature 13 will cause the pawl 31 to advance the ratchet wheel 27 in a clockwise direction, the pawl 30 sliding over the teeth of the ratchet wheel. Upon the deenergizing of coil 7, the spring 14 will cause the armature 13 to move in the opposite direction. This movement will cause the pawl 30 to advance the sprocket wheel 27 in a clockwise direction, and at the same time the pawl 31 will slide over the teeth of the sprocket wheel and assume a position for its next operation in advancing the sprocket wheel as before. So long as the armature 13 continues to vibrate, the sprocket wheel will rotate and drive the rotary tool connected thereto. The cuticle pusher 21 may also be used to stop the rotation of the rotary tool. Since the cuticle pusher is in direct connection with the armature 13, it is evident that the advancement of the ratchet wheel may be prevented by the operator of the device pushing against the

cuticle pusher so that the armature will not be able to vibrate. This is an advantage in that the operation of the rotary tool may be temporarily stopped without electrically disconnecting the device.

The operation of the device from a direct current supply will be the same as when operating from an alternating current source, except that the plug is inserted in the socket so as to make connection with the prongs A and C. This connection inserts the make and break device in one side of the circuit to the coil, so that, when the coil is energized, the armature 13 will be attracted as before and move against the resistance of the spring 14. This movement of the armature will cause the contact 54 to move away from contact 53, thereby disconnecting one side of the circuit to the coil, which now becomes deenergized. The coil being deenergized, the armature will be moved upwardly by the spring 14, contact 54 will engage contact 53 and re-establish the circuit through the coil, which being again energized will attract the armature 13 as before. This operation will continue so long as direct current is supplied to the device, or until the device is stopped by the operator's pressing upon the cuticle set 21. The operation of the ratchet mechanism will be the same as when operating from an alternating current supply.

This invention, therefore, provides a power manicuring device which is compact in construction, easy to use, which may be operated either from direct or alternating current, and which uses a rotary tool, said tool being easily and quickly detached from the device for replacing with a tool for performing some other operation incident to manicuring.

I am aware that numerous details of construction may be varied through a wide range without departing from the spirit of this invention, and I, therefore, do not purpose limiting the patent granted otherwise than is necessitated by the prior art.

I claim as my invention:

1. An electrical manicuring device comprising a casing, a coil in said casing, an armature supported at one end and responsive to said coil, a pair of spring pawls carried by said armature, a ratchet wheel alternately rotated by each of said pawls, and a tool connected to said ratchet wheel and rotatable therewith, said tool extending to the exterior of said casing.

2. An electrical manicuring device comprising a casing, a coil in said casing, an armature supported at one end and responsive to said coil, a pair of spring pawls carried by said armature, a ratchet wheel alternately rotated by each of said pawls, a tool connected to said ratchet wheel and rotatable therewith, said tool extending to the exterior of said casing, and means manually operable

- from the exterior of said casing for starting and stopping said tool.
3. A manicuring device comprising a casing, a coil in said casing, an armature influenced by said coil, a vibratable tool carried by said armature and projecting to the exterior of said casing, and a rotary tool outside of said casing connected to said armature and operable simultaneously with said vibratable tool.
- 10 4. A manicuring device comprising a casing, a coil in said casing, a movable arm responsive to said coil, a circuit interrupter connected to said arm for breaking the electrical circuit to said coil when said arm is moved in one direction, a spring for moving said arm in the other direction to re-establish the electrical circuit to said coil, means connected to said arm for converting its movement into rotary motion and a rotary tool exterior of said casing having a portion projecting inside of said casing for connection with said means.
- 15 5. A manicuring device comprising a casing, power means in said casing having a rotatable member projecting through said casing, a rotary tool disposed outside of said casing and removably connected to said member, and a finger rest disposed on each side of the plane of rotation of said tool, one of said finger rests being pivotally movable to remove said tool.
- 20 6. A manicuring device comprising a casing, power means in said casing having a rotatable member projecting through said casing, a rotary tool operative outside of said casing having a sleeve coaxially engaging said member, a guard plate pivotally connected to said casing and normally extending over said tool, and means for latching said plate in normal position.
- 25 7. A manicuring device comprising a casing, electric power means in said casing including a rotary member projecting externally of said casing, a rotary tool outside of said casing removably connected to said member, and means whereby said power means is connectible for operation on direct current as well as alternating current.
- 30 8. A manicuring device comprising a vibratable tool, a rotary tool, and power means to simultaneously actuate said tools.
- 35 9. A power manicuring device comprising a plurality of tools, and means for imparting a vibratory motion to certain of said tools and a rotary motion to the other of said tools.
- 40 10. A power manicuring device comprising a plurality of tools, and means for simultaneously imparting a vibratory motion to certain of said tools and a rotary motion to the other of said tools.
- 45 11. An electrical manicuring device comprising an apertured casing, a vibratable member extending through one of said apertures to the outside of the casing, a rotatable
- member extending through another of said apertures to the outside of the casing, a manicuring tool carried by each of said members, and means within said casing for imparting motion to the respective members.
- 50 12. A manicuring device comprising a vibratable tool, a rotary tool, power means to simultaneously actuate said tools, and connections between said tools, whereby the movement of the rotary tool may be controlled by means of the vibratable tool.
- 55 13. An electrical manicuring device comprising a vibratable member, a rotary member, a manicuring tool carried by each of said members, power means for actuating said vibratable member, and a pawl and ratchet connection between said vibratable member and rotary member, said connection being rendered inactive when the vibratable member is restrained against movement.
- 60 14. A manicuring device comprising a tool, power means for actuating said tool, and means for controlling the actuation of said tool without the necessity of having to de-energize said power means.
- 65 In testimony whereof I have hereunto subscribed my name at Chicago, Cook County, Illinois.
